UNITED STATES PATENT OFFICE.

EUGÈNE GILLET DE MONTMORE, OF VIENNA, AUSTRIA-HUNGARY.

AIR-MOISTENING APPARATUS.

SPECIFICATION forming part of Letters Patent No. 496,525, dated May 2, 1893.

Application filed April 15, 1892. Serial No. 429,252. (No model.)

To all whom it may concern:

Be it known that I, EUGÈNE GILLET DE MONTMORE, a subject of the Emperor of Austria-Hungary, residing at Vienna in Austria-Hungary, have invented certain new and useful Improvements in Apparatus for Moistening and Renewing the Atmosphere, of which the following is a specification.

This invention relates to an improved atomizer or spray diffuser consisting of a pair of concentric pipes, an intermediate perforated ring and a nozzle. The object of the atomizer is to introduce from outside into a closed chamber or room a fresh current of air, which while being supplied is mixed with atomized water.

In the accompanying drawings: Figure 1 is a longitudinal section of my improved atomizer; Fig. 2, a cross-section thereof. Fig. 3 is a longitudinal section of the atomizer showing triplex nozzles. Fig. 4 is a longitudinal section of a modification of the atomizer; Fig. 5, a cross section of Fig. 4 and Fig. 6 is a longitudinal section of a multiplex atomizer constructed according to the modification.

In Figs. 1-3 the letter a' , represents the inner tube adapted to be supplied with compressed air and c , is the concentric outer tube, adapted to be supplied with water.

30 Into the front end of the tube c , a perforated ring d is inserted or screwed, through the central bore of which, passes the air tube a' , the forward end of which is tapering. The ring d projects from the water supply tube c , and to the forward end of said ring a mouth piece e , of tapering shape is screwed. This mouth piece is provided on its inner surface with webs or ribs. The ring d is perforated by several channels in the direction of its length and the current of air issuing from the pointed forward end of the tube a' , draws the water forth through the said passages of the ring and atomizes the same in a manner to form a fine spray or dust of water. By com-

bining several of these atomizers, a triplex or 45 multiplex atomizer may be formed, as shown in Fig. 3. In this case the air may be supplied through a common tube a , from which branch pipes a^2 , a^3 , a^4 , are leading to the several atomizers. In the same manner, water may be 50 fed on through a common tube b , to the main tube c , and thence be branched off to several atomizers or mouth pieces e , from which the spray is diffused into the atmosphere of the room.

55 In Figs. 4 and 5 a modification of the construction of the atomizer is shown. As in the former construction, two tubes a' and c are arranged, one inside the other and a perforated ring d , surrounds the inner tube, as 65 shown and described. The mouth piece e , is mounted on the forward end of the ring d . Both the mouth piece e and tube a' , are perforated at their forward ends, the perforation of the tube a' , being shown at e' . In this case 70 water is supplied through the central tube a' and air through the outer tube c . Within the hollow space of the mouth piece e , water and air will become mixed and be forced out of the fine apertures of the mouth piece e , in 75 the form of a finely divided spray. This modified construction, as that described before, may be embodied in a multiplex arrangement, as illustrated in Fig. 6.

I claim—

75 An atomizer or spray diffuser consisting of two pipes a' and c , one arranged inside the other, a hollow perforated ring d , inserted into the outer pipe and surrounding the inner pipe, serving to combine the two, in combination with a mouth piece or nozzle e , secured to the said ring d , substantially as specified.

80 Signed at Vienna, Austria-Hungary, this 28th day of March, 1892.

EUGÈNE GILLET DE MONTMORE.
